UNITED STATES PATENT OFFICE

HOWARD H. CRAWFORD, OF DETROIT, MICHIGAN, ASSIGNOR TO PINES WINTERFRONT COMPANY, OF CHICAGO, ILLINOIS, A CORPORATION OF DELAWARE

COOLING APPARATUS

Application filed February 27, 1931. Serial No. 518,735.

This invention relates to cooling apparatus for internal combustion engines in which circulating liquid is employed as the cooling medium.

5 Among the objects of the invention are to provide an improved cooling apparatus for this purpose; to provide improved means whereby the liquid circulation may be bypassed and controlled; and to provide improved means whereby the circulation, bypass of liquid and heat radiation may be 10 regulated from a single control and in desired order.

Other objects, advantages and capabilities 15 of the invention will appear from the following description of a preferred embodiment, taken in conjunction with the accompanying drawings, in which

Figure 1 is a diagrammatic view, partly in 20 section, of an automobile engine and associated parts, embodying the invention;

Fig. 2 is a sectional detail view on the line 2-2 of Fig. 1;

Fig. 3 is a sectional view taken on the line 25 3-3 of Fig. 2; and

Fig. 4 is a sectional plan detail view taken on the line 4-4 of Fig. 2.

Referring to the drawings, the reference numeral 10 designates an internal combustion 30 engine, the water jacket of which is connected by upper conduit 11 and by lower conduit 12 to the radiator 13. A pump 14 is provided in the lower conduit 12 in order to circulate the liquid cooling medium through the engine 35 block and radiator.

In front of the radiator 13 is mounted a shutter 15 which controls the flow of air through the radiator and the degree of cooling of the liquid therein. The shutter may 40 be of any suitable type and may be actuated by a link 16 which is secured to a bell crank lever 17 pivotally mounted on the top of the shutter frame. The lever 17 is actuated by a rod 18 which passes through a tube 19 in the 45 top water box 20 of the radiator 13.

In the drawings I have shown a shutter 15 comprising a series of vertical shutter elements 21, pivotally mounted in the shutter frame. Each shutter element is provided 50 with a lug 22, and said lugs are pivotally con-

nected to an actuating bar 23 which is located below the top frame member of the shutter frame. A stud 24 mounted on the actuating bar 23 projects through an arcuate slot 25 in the top frame member, and the link 16 is pivotally connected thereto. A tension spring 26 connects the stud 24 to a lug 27 on the top frame member so that the shutter elements 21 automatically close except when the link 16 is actuated by the rod 18 to move them to their open position.

Adjacent the tube 19 the rear wall of the upper water box 20 is provided with a relatively large opening 31 and an inwardly directed flange 32, to which is welded, soldered or otherwise secured a collar 33. The collar 33 projects rearwardly from the water box 30 and is provided at its rear end with a flange 34. On one side the collar 33 is provided with an inlet port 35 and a shoulder 36 whereby the end member 37 of the upper conduit 11 may be bolted or otherwise secured thereto. The collar 33 is provided with a threaded opening 38 which receives a by-pass pipe 39, which is arranged in parallel with the radiator 13 so that the circulation of the cooling medium may be diverted therethrough in whole or in part as will herein-after appear. The by-pass pipe 39 may suitably be connected to the lower conduit 12 at 50 a suitable point. The collar 33 provides a support for a casing 40 which is provided at its open end with a flange 41 adapted to overlie with the flange 34. A cover plate 42 is secured to the flange 34 by screws 43, suitable 55 gaskets 44 being provided on either side of the flange 41 so as to prevent leakage from the casing 40. While it is preferred to locate the casing 40 in the upper water box of the radiator, it will readily be understood that 60 it may be mounted in any other desired position in the circulatory system, for example, in the lower water box or on the engine block.

The inner end of the casing 40 is provided with a relatively large opening which is 65 adapted to be closed by a valve 46. The valve 46 is mounted on a stem 47 which is supported by a spider 48 and is secured to one side of a thermostat 49 which may suitably be constituted by an expandible metal bellows con- 70

taining volatile liquid of appropriate boiling point. The outer end of the thermostat 49 rigidly carries a threaded stud 50a which is threaded into a coupling 51. The coupling 51 also receives the threaded end of a spindle 50 which extends through a packing gland 52 on the cover plate 42.

The casing 40 is provided with ports 53 which register with the port 35, and with an opening 54 which registers with the opening 38. Adjacent this opening a reinforcing strip 55 of similar curvature is rigidly mounted upon the interior of the casing 40, said strip being provided with an opening 56 registering with the openings 38 and 54. A valve member 57 is adapted to close the opening 56, said valve member being of the same curvature as the strip 55 and adapted to slide thereon. The valve member 57 is supported from the rearward part of the thermostat 49, for example, by means of a vertical web 58 which is engaged between the coupling 51 and the rear face of the thermostat, said web being provided with an opening through which the stud 50 passes.

The rearwardly projecting ends of the rod 18 and spindle 50 are pivotally connected to a link 59 which is fulcrumed at an intermediate point so that the rod 18 and spindle 50 move in opposite directions. Preferably the connections between the link 59 and the rod 18 and spindle 50 are adjustable so that the device may be readily adapted for the best operation. The link 59 may suitably be formed of two straps welded or otherwise secured together, the ends of which are displaced to provide the link with bifurcations at both ends. The bifurcated ends are provided with openings 60 which receive pintles 61 of collars 62 and 63 mounted on the threaded ends of the rod 18 and spindle 50 respectively. The collar 63 may have a threaded engagement upon the spindle 50 and may be locked in position by a lock nut. The collar 62 may be freely movable on the rod 18 and may be located in desired position by lock nuts on either side.

The link 59 is pivotally connected at an intermediate point to a link 64 of similar construction. The other end of the link 64 is pivotally connected to a web 65 formed on the cover plate 42. As will readily be understood from Fig. 4, this system of linkage provides a slight lateral movement of the rod 18 during its longitudinal movement, while the spindle 50 is constrained to axial movement only.

The operation of the cooling apparatus is as follows: Assuming the engine to be cold, the shutter 15 is closed and the thermostat and associated elements are in the condition shown in Fig. 3. The valve 46 closes the opening 45 and the by-pass port 56 is open. When the engine is put into operation, the pump 14 circulates cooling fluid through the

engine water jacket, casing 40 and by-pass pipe 39. Since there is practically no radiation of heat, the engine warms up rapidly. When the temperature of the circulating liquid attains a certain degree, depending upon the adjustment of the device, the thermostat 49 expands sufficiently to open the valve 46, the spring 26 preventing the movement of the spindle 50 until the forward end of the thermostat 49 abuts against the spider 48. The opening of the valve 46, gradually at first, permits circulation through the radiator 13 as well as through the by-pass pipe 39 until all the cooling medium is warmed up. Further rise of temperature is accompanied by a further expansion of the thermostat 49 which moves the spindle 50 outwardly so as to open the shutter 15. At the same time the valve member 57 progressively closes off circulation through the by-pass 39. When the coupling 51 abuts against the cover plate 42, the shutter 15 is completely open and the by-pass 39 is completely closed.

When the cooling liquid temperature falls, the thermostat 49 will collapse to close or partly close the shutter 15 and open or partly open the by-pass 39 so as to maintain the temperature of the engine block at the desired level.

Although the invention has been disclosed in connection with the specific details of a preferred embodiment, it must be understood that such details are not intended to be limitative of the invention, except insofar as set forth in the accompanying claims.

What I claim as new and desire to secure by Letters Patent is:

1. An engine cooling system for automotive vehicles comprising a radiator and engine water jacket in series, a by-pass in parallel with the radiator, a thermostat free to expand in one direction to open circulation through the radiator, means opposing expansion in the opposite direction, and a valve adapted to be operated by last said expansion to close said by-pass.

2. An engine cooling system for automotive vehicles comprising a liquid circulatory system including a water jacket and radiator, a by-pass for said radiator, a valve adapted to control flow through the radiator, a valve adapted to control flow through the by-pass, and a thermostat adapted by its expansion in one direction to open the first said valve and thereafter by expansion in the opposite direction close the second said valve with progressively increasing temperature.

3. An engine cooling system for automotive vehicles comprising a liquid circulatory system including a water jacket and radiator, a chamber in said circulatory system, a by-pass from said chamber in parallel with the radiator, a valve controlling the flow of liquid from the chamber to the radiator, a valve controlling the flow of liquid from the

- chamber to said by-pass, and a thermostat within said chamber adapted by its expansion in one direction to open the first said valve and thereafter by expansion in the opposite direction to close the second said valve with progressively increasing temperature.
4. In an engine cooling system, a thermostat exposed to the cooling medium, a radiator, a by-pass therefor, a valve adapted to control flow through the radiator, a valve adapted to control flow through the by-pass, a thermostat adapted to effect free movement of the first said valve to open same, means limiting said movement, and means resiliently opposing opposite movement by the thermostat, the last said movement being adapted to close the last said valve.
5. In an engine cooling system, a thermostat exposed to the cooling medium, a radiator, a by-pass therefor, a valve carried by one side of the thermostat adapted to be opened by the expansion of the thermostat, means limiting the movement of the valve in open position, a valve carried by the other side thereof adapted to be closed by the expansion of the thermostat, and a spring opposing the movement of last said valve, whereby the first said valve is adapted to open before the last said valve closes.
6. An engine cooling system for automotive vehicles comprising a radiator and engine water jacket in series, a by-pass in parallel with the radiator, a thermostat free to expand in one direction to open circulation through the radiator, means opposing expansion in the opposite direction, a valve adapted to be operated to close said by-pass, and a radiator shutter adapted to be opened by last said expansion.
7. An engine cooling system for automotive vehicles comprising a liquid circulatory system including a water jacket and radiator, a by-pass for said radiator, a valve adapted to control flow through the radiator, a valve adapted to control flow through the by-pass, a shutter for controlling the flow of air through the radiator, and a thermostat adapted to open the first said valve and thereafter close the second said valve and open the shutter with progressively increasing temperature.
8. An engine cooling system for automotive vehicles comprising a liquid circulatory system including a water jacket and radiator, a shutter for controlling the flow of air through said radiator, a chamber in said circulatory system, a by-pass from said chamber in parallel with the radiator, a valve controlling the flow of liquid from the chamber to the radiator, a valve controlling the flow of liquid from the chamber to said by-pass, and a thermostat within said chamber adapted to open the first said valve, and thereafter to close the second said valve and open the shutter with progressively increasing temperature.
9. In an engine cooling system, a thermostat exposed to the cooling medium, a radiator, a by-pass therefor, a shutter adapted to control the flow of air through the radiator, a valve adapted to control the flow of cooling liquid through the radiator, a valve adapted to control the flow of cooling liquid through the by-pass, a thermostat adapted to effect free movement of the first said valve to open same, means limiting said movement, and means resiliently opposing opposite movement by the thermostat, the last said movement being adapted to close the last said valve and open the shutter.
10. In an engine cooling system, a thermostat exposed to the cooling medium, a radiator, a by-pass therefor, a valve carried by one side of the thermostat adapted to be opened by the expansion of the thermostat, means limiting the movement of the valve to open position, a valve carried by the other side of the thermostat adapted to be closed by the expansion of the thermostat, a radiator shutter adapted to be opened by said expansion, and a spring opposing the movement of last said valve and shutter whereby the first said valve is adapted to open before the last said valve closes.
11. In an internal combustion engine, in combination, a circulatory cooling medium system including an engine water jacket and radiator, a valve adapted to close the flow through the radiator, a shutter adapted to control the flow of air through the radiator, and thermostatic means actuated by the temperature of the cooling medium adapted to open the radiator valve when a predetermined water jacket temperature is reached, and to open the shutter when a higher predetermined temperature is reached.
12. An engine cooling system for automotive vehicles comprising a radiator and engine water jacket in series, a thermostat free to expand in one direction to open circulation through the radiator, means opposing expansion in the opposite direction, and radiator shutter adapted to be opened by last said expansion.
13. An engine cooling system for automotive vehicles comprising a liquid circulatory system including a water jacket and radiator, a valve adapted to control flow through the radiator, a shutter for controlling the flow of air through the radiator, and thermostat adapted to open the valve and after the opening of said valve to begin to open the shutter with progressively increasing temperature.
14. An engine cooling system for automotive vehicles comprising a liquid circulatory system including a water jacket and radiator, a shutter for controlling the flow of air through said radiator, a chamber in said cir-

- culatory system, a valve controlling the flow of liquid from the chamber to the radiator, and a thermostat within said chamber adapted to open the valve and after the opening of said valve to begin to open the shutter with progressively increasing temperature. 70
13. In an engine cooling system, a thermostat exposed to the cooling medium, a radiator, a shutter adapted to control the flow 10 of air through the radiator, a valve adapted to control the flow of cooling liquid through the radiator, a thermostat adapted to effect free movement of the valve to open same, means limiting said movement, means resiliently opposing opposite movement by the thermostat, last said movement being adapted to open the shutter. 75
14. In an engine cooling system, a thermostat exposed to the cooling medium, a radiator, a valve carried by one side of the thermostat adapted to be opened by the expansion of the thermostat, means limiting the movement of the valve to open position, a radiator shutter, means carried by the other 20 side of the thermostat whereby the shutter is adapted to be opened by the expansion of the thermostat, and a spring opposing the movement of the shutter, whereby the valve is adapted to open before the shutter opens. 80
15. 17. In combination in an engine cooling system, a radiator and engine water jacket in series, a by-pass in parallel with the radiator, a valve controlling the flow of liquid from the water jacket to the radiator, a second valve controlling the flow of liquid through said by-pass, a shutter controlling the flow of air through said radiator, and a thermostat adapted to expand in one direction to open said first valve and, after the opening of said first valve, to expand in the opposite direction to open the shutter and shut the by-pass valve. 85
16. In combination in an engine cooling system, a radiator and engine water jacket in series, a by-pass in parallel with the radiator, a valve controlling the flow of liquid from the water jacket to the radiator, a shutter controlling the flow of air through said radiator, and a thermostat adapted to expand in one direction to open said valve and, after the opening of said valve, to expand in the opposite direction to open the shutters. 90
17. In combination in an engine cooling system, a radiator and engine water jacket in series, a by-pass in parallel with the radiator, a valve controlling the flow of liquid from the water jacket to the radiator, a second valve controlling the flow of liquid through said by-pass, a shutter controlling the flow of air through said radiator, and a thermostat adapted under the influence of increased temperature first to open said first valve and subsequently to open the shutters and close said second valve. 95
18. In combination in an engine cooling system, a radiator and engine water jacket in series, a by-pass in parallel with the radiator, a valve controlling the flow of liquid from the water jacket to the radiator, a shutter controlling the flow of air through said radiator, and a thermostat adapted to expand in one direction to open said valve and, after the opening of said valve, to expand in the opposite direction to open the shutter and shut the by-pass valve. 100
19. In combination in an engine cooling system, a radiator and engine water jacket in series, a by-pass in parallel with the radiator, a valve controlling the flow of liquid from the water jacket to the radiator, a second valve controlling the flow of liquid through said by-pass, a shutter controlling the flow of air through said radiator, and a thermostat adapted under the influence of increased temperature first to open said first valve and subsequently to open the shutters and close said second valve. 105
20. In combination in an engine cooling system, a radiator and engine water jacket in series, a by-pass in parallel with the radiator, a valve controlling the flow of liquid from the water jacket to the radiator, a shutter controlling the flow of air through said radiator, and a thermostat adapted when subjected to increased temperature first to open said valve and, after the opening of said valve, to open said shutter. 110
21. In combination in an engine cooling system, a radiator and engine water jacket in series, a by-pass in parallel with the radiator, a valve controlling the flow of liquid from the water jacket to the radiator, a second valve controlling the flow of liquid through said by-pass, and a thermostat adapted to expand in one direction to open said first valve and, after the opening of said first valve, to expand in the opposite direction to open said second valve. 115
